UNITED STATES PATENT OFFICE.

JAMES W. TIFFANY, OF BUCHANAN, MICHIGAN.

CAMPING STOVE.

Application filed May 25, 1920. Serial No. 384,057.

To all whom it may concern:

Be it known that I, JAMES W. TIFFANY, a citizen of the United States, residing at Buchanan, in the county of Berrien and State of Michigan, have invented certain new and useful Improvements in Camping Stoves, of which the following is a specification.

This invention relates to improvements in camping stoves.

The main object of this invention is to provide an improved camping stove which is very efficient and at the same time is light in weight and may be collapsed into a comparatively small package for transportation or storage.

Further objects, and objects relating to structural details, will definitely appear from the detailed description to follow.

20 I accomplish the objects of my invention by the devices and means described in the following specification. The invention is clearly defined and pointed out in the claims.

A structure which is a preferred embodiment of my invention is clearly illustrated in the accompanying drawings, forming a part of this application, in which:

Fig. I is a side elevation of my improved camping stove collapsed, portions being broken away to better show the parts in this position.

Fig. II is a side elevation of my improved stove erected.

Fig. III is a detail longitudinal section on the line corresponding to line 3—3 of Fig. IV.

Fig. IV is a front elevation, the flue being omitted.

Fig. V is a plan view with the parts assembled as in Fig. I.

Fig. VI is a side elevation corresponding to that of Fig. I with the front section collapsed within the rear section in position to be drawn forward or extended, parts being broken away to show structural details.

Fig. VII is a side elevation with the rear section telescoped upon the outside of the front section, parts being broken away to show structural details.

In the drawings similar reference characters refer to similar parts throughout the several views.

Referring to the drawings, my improved stove has a tubular rearwardly tapered body comprising a front section 1 and a rear sec-

tion 2. These sections are adapted to be joined by telescoping engagement either with the rear section within the front as shown in Figs. II, III and V, or with the rear section upon the front section as shown in Fig. VII. The top 4 of both body sections is flat, thus providing a flat top for the stove. The side and bottom walls of the sections are curved.

The flue comprises an elbow portion 5 and an upright portion 6, the upright portion being upwardly tapered. The flue is telescoped upon the reduced portion 7 at the rear end of the section 2 of the body.

The parts are held in their telescoped assembled relation by means of the hasp-like coupling members 8, there being a coupling member secured to each side of the rear body section to coact with staples 9 at the rear end of the front body section, pins 10 being arranged through the staples to prevent the disengagement of the coupling. A similar coupling member 8 is arranged on the top of the elbow of the flue so that when the flue is assembled upon the body the hasp engages the staple 9 at the rear end of the rear body section. With the sections thus joined the stove may be handled as a unit, the section joints being secure and not likely to become disengaged.

To permit the hasp 9 to swing out to staple engaging position when the rear section is telescoped within the front section the front section is slotted at 3. When the rear section is arranged on the outside the telescoping relation is not so great and to accommodate this the hasp members are provided with a plurality of holes 8', one being adapted to engage the staple when adjusted as in Fig. II, and the other when adjusted as in Fig. VII. The parts may be quickly assembled and disassembled when arranged in either relation.

The front body member has a horizontally disposed foraminated plate 11 therein constituting a grate. Below this grate is a front wall 12 provided with a damper 13 so that air may be admitted below the grate.

The door 14 is hinged at its upper end to the rear edge at the top as at 15 so that it may be swung open to fully open the front end of the stove for the placing of fuel therein or the nesting of the parts as will be hereafter described.

A latch 16 is provided for the door. The door also has a stop 17 which prevents its

falling rearwardly on the top when swung to a vertical position.

When the sections are disassembled the flue may be nested or arranged within the rear body section and the rear body section with the flue therein is nested within the front body section as shown in Fig. I.

I provide a pair of front legs 18 which are adjustably secured to the sides of the front body section 1 at the front end thereof by means of the thumb nuts 19 engaging the slots 18'. A third leg 20 is detachably secured to the under side of the rear body section 2 by means of the thumb nuts 21. The legs are longitudinally slotted at 18' to receive the securing bolts so that they may be collapsed against the sides of the front body member as shown in Fig. I. The front leg is detachably secured, as stated, so that it may be removed and arranged within the collapsed parts, as shown. In Fig. VII the leg 18 is shown in a forwardly inclined position, its upper end resting against the bead on the front section. When thus arranged the legs are held at two points. It is not necessary to clamp the nuts 19 tightly.

My improved stove is light in weight, it being formed of sheet metal, and at the same time is durable and efficient.

I have illustrated and described my improvements in a form in which I have embodied them in practice. I have not attempted to illustrate and describe certain modifications in structural details which I contemplate as I believe the disclosure made will enable those skilled in the art to which my invention relates to embody or adapt the same as may be desired.

Having thus described my invention, what I claim as new and desire to secure by Letters Patent, is:

1. In a camping stove, the combination of a tubular rearwardly tapered body having

a flat top and curved side and bottom walls 45 comprising detachable front and rear body sections, a foraminated plate disposed horizontally in the front body section constituting a grate, the front section being provided with a wall below said grate having a 50 damper therein and with a door above said grate hinged at its upper end and overlapping and closing against the front edges of the side walls and grate, a flue comprising an elbow and an upwardly tapered upright 55 portion, said elbow telescoping with the rear end of the rear body section, the parts when in the knockdown being adapted to be nested with the flue within the rear body section, and the rear body section with the 60 flue therein within the front body section, and couplings for said parts comprising hasps mounted on one part to engage staples on the adjacent part.

2. In a camping stove, the combination of 65 a tubular rearwardly tapered body having a flat top and comprising telescoping front and rear body sections, a foraminated plate disposed horizontally in the front body section 70 constituting a grate, the front section being provided with a wall below said grate having a damper therein and with a door above said 75 grate hinged at its upper end and overlapping and closing against the front edges of the side walls and grate, a flue portion telescoping with the rear end of the rear body section, the parts when collapsed being adapted to be nested with the flue within the rear body section and the rear body section with the flue therein 80 within the front body section.

In witness whereof I have hereunto set my hand and seal.

JAMES W. TIFFANY. [L.S.]
